UNITED STATES PATENT OFFICE.

WILLIAM L. WALKER, OF NEW YORK, N. Y.

VAULT LIGHT.

1,418,341.

Specification of Letters Patent. Patented June 6, 1922.

Application filed May 3, 1919. Serial No. 294,381.

To all whom it may concern:

Be it known that I, WILLIAM L. WALKER, citizen of the United States, and resident of New York city, in the county of New York and State of New York, have invented new and useful Improvements in Vault Lights, of which the following is a specification.

This invention relates to a frame for vault lights and more particularly to a vault light frame adapted to be completely formed and assembled before being installed. My improved vault light frame is particularly adapted to be employed in sidewalks to illuminate the space therebeneath but it is applicable in any situation where a covering is desired which will both transmit light and also be substantial, as for example a cover for inside courts, sun parlors, green-houses, etc.

Heretofore in installing vault lights in sidewalks it has been customary to build a floor under the sidewalks, to place the glass lenses in a beaver board which has been perforated at proper intervals to hold the lenses in spaced relationship, then to lay in reinforcing rods between the lenses and finally to fill the space between the lenses with a cement or the like. When employing this mode of construction carpenters must first be employed to build the floor; the carpenters are then followed by the workmen who install the vault light lenses and tie-rods and cement; and then the installation must be left for a considerable period of time to permit the cement to set. After the cement has set the wooden floor must be removed. Thus the installation not only takes considerable time but it is also unduly expensive. Moreover, in busy streets this method of construction is also highly objectionable for the reason that it obstructs the sidewalk for a considerable period of time, frequently for a week or more.

The principal object of the present invention is to overcome the aforesaid difficulties and to provide a vault light construction which can be completely assembled before being installed, so that only a relatively small amount of time and labor is required in making an installation. Another object is to provide a vault light frame which is rigid and substantial and which is at the same time easy and inexpensive to construct. Still another object of the invention is to provide improved means

for the prevention of slipping on the vault light after it has been installed.

In the accompanying drawings which illustrate certain preferred embodiments of the invention,—

Figure 1 is a plan view of one embodiment, with a portion of the cement or filling material broken away to show the frame construction;

Figure 2 is a plan view of another embodiment, showing a modified frame construction having a reinforcing wire mesh and with the cement or other filling material applied to a portion of the frame;

Figure 3 is a section on line 3—3 of Fig. 2;

Figure 4 is a section on line 4—4 of Fig. 1;

Figure 5 is a section of a further embodiment showing wire mesh strips inserted between the longitudinal members of the frame;

Figure 6 is a section on line 6—6 of Fig. 5;

Figures 7 to 12 inclusive are sections of modified forms of frame members;

Figure 13 is a section through a glass lens and its supporting frame showing a frame having substantially the same cross-section as shown in Fig. 9;

Figure 14 is a perspective detail view of a portion of a frame constructed from members having the same cross-section as shown in Fig. 10;

Figure 15 is a perspective detail view of a portion of a further modified frame having small intermediate ribs in the form of rods for retaining the cement or other filling in place;

Figure 16 is a longitudinal section of a frame member showing one method of attaching a safety tread;

Figure 17 is a section on line 17—17 of Fig. 16;

Figure 18 is a section of a frame member and modified form of safety tread;

Figure 19 is a longitudinal section of a frame member showing a further method of attaching a safety tread, and further showing the frame member bowed downwardly for greater strength;

Figure 20 is a section on line 21—21 of Fig. 19, with the safety tread omitted; and

Figure 21 is an enlarged sectional view of a lens and supporting frame, such as shown in Fig. 3.

The embodiment of my invention illustrated in Figs. 1 and 4 comprises a frame F having a network of longitudinal and transverse members L and T which may be connected together at certain of their junctions by annular members A. The longitudinal and transverse members are further connected by intermediate longitudinal and transverse members or ribs I of lighter cross-section than the frame members L and T, and the annular members A are similarly connected by intermediate members or ribs D of substantially circular cross-section, as shown in Figs. 1 and 4. The spaces S between the main frame members are filled with cement C or other suitable material depending on the use to which the device is to be put. The intermediate frame members I and D being of less cross-section than the main frame members, thus become entirely embedded in the cement and act as reinforcing members. To further secure the cement or the like in the spaces S and to prevent it from being displaced by walking upon it, the frame members are tapered upwardly and downwardly so that they have greatest cross-section at their mid-portion M as shown in Fig. 4. Each of the frame members, including the longitudinal members L, the transverse members T, the intermediate members I and the annular members A, are preferably tapered in this manner. The annular members A are tapered downwardly on the inside and are thus adapted to support the glass lenses G, the lenses being spaced from the annular members by bushings B of rubber or other suitable material and being held in the annular members by means of hooks h, extending through lugs f provided at the bottom edge of the members A, and into recesses in the sides of the lenses, this means for mounting lens glasses being described and claimed in my former Patent No. 1,258,066, granted March 5, 1918.

The preferred embodiment of my invention, illustrated in Figs. 2 and 3 is similar to that shown in Figs. 1 and 4 in that it comprises a frame F having longitudinal members L, transverse members T, annular members A, and glass lenses G mounted in the annular members. It differs from the frame shown in Figs. 1 and 4, in that the intermediate frame members are omitted and the longitudinal and transverse members are cut down in height and a sheet of wire mesh N is cut to fit inside the frame F and rests on top of the longitudinal and transverse frame members. Openings O are punched in the mesh to allow the annular members A to project through it. The mesh thus forms a reinforcement for the cement or other suitable material which is filled into frame F.

Obviously a frame could be constructed having intermediate frame members I and

D also using wire mesh as shown in Fig. 2 for further reinforcement.

Instead of cutting down both the longitudinal members L and transverse members T, which would weaken the frame to some extent, only the transverse members T may be cut down, and instead of a single sheet of wire mesh covering the entire frame, strips of mesh M may be cut to fit between the longitudinal members L and rest upon the top of the transverse members T, as shown in Figs. 5 and 6.

In Figs. 7 to 12 inclusive I have shown several cross-sections of frame members which may be used. Figure 8 shows the preferred embodiment, however, this cross-section giving greatest strength with the least weight of metal. It will be noted that it is in the general form of an I beam with the top of the beam narrower than the bottom thus exposing a small metal area on the wearing surface of the vault construction. In Figure 13 I have shown the annular member A as having an outside surface similar to the side of the section shown in Fig. 9.

The longitudinal frame members L and transverse members T may have the cross-section shown in Fig. 10 and when cast would appear as shown in Fig. 14. This form of construction is well adapted to the use of wire mesh as shown in Figs. 5 and 6.

In Fig. 15 I have shown a further embodiment of my invention, similar to Fig. 1 except that two modified forms of reinforcing members are shown connecting the longitudinal and transverse members L and T of the frame. In one form the reinforcing members are shown as rods J circular in cross-section and cast integrally with the frame. In the second form the reinforcement comprises a thin web of metal J¹ which may be formed by slightly separating the two halves of the flask when the frame is cast, thus allowing metal to flow between the members L and T forming the web. After being cast the web J¹ could be punched full of holes J² to allow the concrete filler to pass from one side of the web J¹ to the other, thus binding the concrete firmly in the frame and thus reinforcing it. This metal web would serve much the same purpose as the wire mesh illustrated in Fig. 2.

It is obvious either or both of the forms of reinforcement illustrated in Fig. 15 could be used in a single frame.

Another phase of my invention illustrated in Figs. 16, 17, 18, 19 and 20, involves safety treads ST which are preferably disposed along the top of the longitudinal and transverse members L and T. These safety treads are preferably T-shaped in cross-section as illustrated in Fig. 17, the vertical portions of the treads fitting into slots s in the upper surfaces of members L and T and the

transverse portions of the treads resting on the upper surfaces of the members L and T. The ends of the safety treads ST are preferably tapered as shown in Fig. 16 to assist in holding the treads in the slots and cooperating with the tapered ends are wedges *w* having inclined faces engaging said beveled ends, the wedges *w* being secured in the ends of the slots by means of screws *s*.
10 The safety treads instead of being T-shaped may be rectangular in cross-section as shown at ST, Fig. 18.

In Figures 19, 20, I have shown a preferred method of holding the safety treads ST in the slots *s* in the members L and T. The ends of the safety treads are tapered and screws *s* having wedge-shaped heads *w* cooperate therewith to hold the treads in the slots. In view of the fact that considerable metal is cut away to form the slot to receive the tread, I have shown the frame member L bowed downwardly at E for reinforcement.

The preferred method of assembling my improved vault light is as follows: The frame is first cast with all of the parts L, T, I, D and A integrally connected together. After the frame has been thus formed the spaces S are filled with cement or the like and the cement is allowed to set. The glasses G are then mounted in the openings in the annular members A. When employing the form of construction shown in Fig. 2, the frame is first cast with all the frame parts integrally connected together. A sheet of wire mesh is then cut just large enough to fit inside the frame F, with holes punched therein large enough to allow the annular members A to pass therethrough, and is then placed into the frame F resting on the members L and T. The entire frame with the exception of the annular members A, is then filled with cement. When employing the safety treads as illustrated in Figs. 1, 16, 17, 18, 19 and 20, the treads are mounted after the cement has been applied. Thus the vault light can be completely assembled before being installed, and indeed the vault light is preferably completely assembled at the factory before being transported to the place of the installation.

One of the salient features of the invention resides in the mode of construction and application of the safety treads whereby they are readily detachable and may be replaced when worn down, the treads preferably being formed of lead or a composition of lead and emery which is adapted to prevent slipping but which may not be as durable as the other parts of the construction. Another improved feature of the invention resides in cross-sectional shaping of the frame members, whereby a maximum of strength for a minimum of metal is obtained with a further result that the cement

which fills in the spaces between the frame members is supported in part by the sides of the frame members. A still further improved feature of the invention resides in the employment of wire mesh whereby a very strong and rigid construction is obtained.

I claim:

1. A vault light frame comprising a plurality of members secured together with spaces therebetween, said members having a cross-section with bowed sides so as to hold cement, or the like in said spaces, and said frame having an opening therethrough adapted to support a lens therein and removable means for positively retaining a lens in said opening.

2. A vault light frame comprising a plurality of members integrally cast together with open spaces therebetween, said members being adapted to hold cement or the like for filling said spaces, and said frame having openings therethrough adapted to support lenses therein, said openings tapering downwardly in diameter.

3. A vault light frame comprising a network of longitudinal and transverse members integrally cast together with open spaces therebetween, said members tapering upwardly in cross-section throughout at least a portion of their depth so as to hold cement or the like for filling said spaces, and said frame having socket openings therethrough having inclined walls for supporting engagement with lens seated therein.

4. A vault light frame comprising a network of longitudinal and transverse members integrally cast together with open spaces therebetween, said members tapering upwardly in cross-section throughout at least a portion of their depth so as to hold cement or the like in said spaces, said openings tapering downwardly in diameter.

5. A vault light frame comprising a plurality of members arranged in intersecting planes and with spaces therebetween, said members having a substantially I-shaped cross-section so as to hold cement or the like in said spaces, and rigid members of less vertical depth than said I shaped members for holding the latter in fixed relation, said frame having socket openings therethrough adapted to support lenses therein.

6. A vault light frame comprising a plurality of rigid members secured together with open spaces therebetween, said members having a cross-section with inwardly bowed sides so as to hold cement or the like for closing said spaces, said frame having socket openings therethrough adapted to support lenses therein and means for retaining lenses within said openings.

7. A vault light frame comprising a plurality of members secured together with open spaces therebetween, said members hav-

- ing a substantially I-shaped cross-section so as to hold cement or the like for filling said spaces, the top surfaces of said members being narrower than the bottom surfaces, and 5 constructed and arranged to lie substantially in the plane of and to form a portion of the wear surface of the frame, and said frame having openings therethrough adapted to support lenses therein.
- 10 8. A vault light frame comprising a plurality of members secured together with spaces therebetween said members adapted to hold cement or the like in said spaces, a wire mesh covering said frame, the mesh 15 and frame having openings therethrough adapted to receive and support lenses therein.
9. A vault light frame comprising a plurality of members secured together with spaces therebetween said members adapted to 20 hold cement or the like in said spaces, a wire mesh covering said frame, the mesh and frame having openings therethrough adapted to receive and support lenses therein and the said mesh adapted to be 25 rounded by said cement.
10. A vault light frame comprising a network of longitudinal and transverse members integrally cast together with spaces therebetween, said longitudinal and trans- 30 verse members being connected together at their junctions by annular members having openings therein adapted to hold lenses and a wire mesh covering said frame and pro- 35 vided with openings punched therein to receive said annular members.
11. A vault light frame comprising a network of longitudinal and transverse members integrally cast together with spaces therebetween, said longitudinal and trans- 40 verse members being connected together at their junctions by annular members having openings therein adapted to hold lenses, the said annular members being of greater height than certain of said members, and a 45 wire mesh covering said frame and provided with openings therein to receive said annular members, so that said mesh lies below the plane of the upper surface of said annular members.
- 50 12. A vault light frame comprising a network of longitudinal and transverse members integrally cast together with spaces therebetween, said longitudinal and trans- 55 verse members being connected together at their junctions by annular members having openings therein adapted to hold lenses, the said annular members being of greater height than said transverse members, and wire mesh covering said frame and so fitted
- as to rest upon said transverse members and 60 below the plane of the upper surface of said annular members.
13. A vault light frame comprising a supporting member of metal having a slot in its upper surface and a safety tread of sub- 65 stantially rectangular cross-section provided with laterally extending flanges and mounted in said slot.
14. A vault light frame comprising a sup- 70 porting member having a rectangular slot in its upper surface, and a T-shaped safety tread having its vertical portion fitted into said slot with its transverse portion resting on members on either side of said slot.
15. A vault light frame comprising a sup- 75 porting member having a slot in its upper surface, and a T-shaped safety tread having its vertical portion fitting into said slot with its transverse portion resting on members on either side of said slot, the ends of said tread 80 being beveled to hold the tread in said slot.
16. A vault light frame comprising a sup- 85 porting member having a slot in its upper surface, a T-shaped safety tread having its vertical portion fitting into said slot with its transverse portion resting on members on either side of said slot, the ends of said tread being beveled, and means overhanging said beveled ends for holding the tread in the 90 slot.
17. A vault light frame comprising a sup- 95 porting member having a slot in its upper surface, a T-shaped safety tread having its vertical portion fitting into said slot with its transverse portion resting on members on either side of said slot, the ends of said tread 95 being beveled, and wedges adapted to be secured in said slot in engagement with said ends for holding the tread in the slot.
18. A vault light frame comprising a sup- 100 porting member having a slot in its upper surface, a T-shaped safety tread having its vertical portion fitting into said slot with its transverse portion resting on members on either side of said slot, the ends of said tread 105 being beveled, and screws having wedge shaped heads screwed in said slot in engagement with said ends for holding the tread in the slot.
19. A vault light frame comprising a net 110 work of metallic supporting members, socket openings at the intersections of said members, and a hook device associated with said socket openings for retaining lenses therein.
- Signed by me at New York city this 8th 115 day of February 1919.

WILLIAM L. WALKER.
